UNITED STATES PATENT OFFICE.

STEPHEN S. GROVES, OF LORAIN, ILLINOIS.

CONVERTIBLE LADDER.

No. 920,733.

Specification of Letters Patent.

Patented May 4, 1909.

Application filed October 13, 1908. Serial No. 457,457.

To all whom it may concern:

Be it known that I, STEPHEN S. GROVES, a citizen of the United States, and a resident of Lorain, in the county of Adams and 5 State of Illinois, have invented certain new and useful Improvements in Convertible Ladders, of which the following is a specification.

This invention is an improvement in ladders and especially in ladders which may be extended or may be converted into step ladders as desired; and the invention consists in certain novel constructions and combinations of parts as will be hereinafter described and claimed.

In the drawings, Figure 1 is a perspective view of my ladder with the supplemental section projecting up to form an extension of the main section. Fig. 2 is a side elevation of the ladder with the supplemental section adjusted to form the prop of a step ladder. Fig. 3 is a detail front view of a portion of the ladder. Fig. 4 is a detail view of one of the guides for the supplemental section. Fig. 5 is a detail view of one of the slide plates carried by the supplemental section, and Fig. 6 is a detail view of one of the supporting devices for the supplemental section.

30 My ladder comprises a main section A, and a supplemental section B slideable along the main section so it can be moved down to the dotted line position shown in Fig. 2, or up to the full line position shown in Fig. 1.

35 The sections are composed each of side bars and rungs as usual in ladders, and the main section A has a top board A' forming a platform, and also has its side bars A² slotted longitudinally at A³ from a point near their lower ends to points near their upper ends. The ends of the step boards A⁴ of the main section are notched in their ends at A' in alinement with the slots A³ and thus form continuations of the said slots.

40 45 Guides C are provided in the form of castings having side plates C' secured to the outer faces of the side bars A² near their upper ends and having flanges C² underlying and secured to the extended ends of the 50 platform A' and operating to brace and support the same.

An arm C³ extends rearwardly from the side plate C' and unites with a lateral inwardly projecting wing C⁴ from which a forwardly 55 projecting wing C⁵ extends forming with the parts C⁴ and C³ a cuff embracing the side bars

of the supplemental section and in which the said side bars are movable longitudinally at their respective sides of the ladder.

The supplemental section B, has its side 60 bars formed with upper main sections B', and with short lower base sections B² hinged together at B³ with the hinge joint so located relatively to the guides C that it will rest below said guides in the extended position of the supplemental section shown in Fig. 1, and above said guides in the step ladder adjustment shown in Fig. 2.

The lower base sections B² are provided with the slides D in the form of plates secured to the base portions B² and extending forwardly therefrom and having inwardly projecting wings D' projecting into and operating within the slots A³.

Plates E are pivoted at E' to the supplemental ladder section and are notched in their ends to engage upon the steps of the main section as shown in Fig. 1, to support the supplemental section B when the latter is extended as shown in said figure. 75 80

A chain F connects the main section and prop as shown in Fig. 2.

It will be noticed that the hinge joint is movable to a point below the guides on the main section when the parts are adjusted as 85 shown in Fig. 1, so that when the ladder is extended as shown in said figure the extension is firmly secured and braced by the said guides on the main section.

The notch in the upper end of the plate E 90 is designed to receive a pin projecting laterally from the ladder, and operating as a stop to limit the movement of the plate E and prevent it from going too far in either direction— 95

I claim—

1. A ladder comprising a main section having its side bars provided with longitudinal slots, guides at the upper ends of said side bars, a supplemental section having an upper or main portion and a lower or base portion and a hinge joint between the two, the side bars of the supplemental section being movable longitudinally in the guides of the main section, and plates secured to the supplemental section and having inwardly projecting wings entering the slots of the main section, substantially as set forth.

2. The combination of a main section having side bars and a top platform extending laterally beyond the side bars, guides having

- main plates secured to the side bars and lateral flanges underlying and secured to the lateral extensions of the platform and the supplemental section having side bars sliding longitudinally in said guides, and composed of sections hinged together, one of said sections being adapted for adjustment to form a step ladder prop, substantially as set forth.
- 10 3. The combination of the main section provided with guides, and the supplemental section having its side bars composed of upper and lower portions, and hinges connecting the same, the said side bars being movable longitudinally in the guides to bring the
- 15

hinge connections above or below the same, substantially as set forth.

4. The combination of the main section having its side bars slotted longitudinally, guides at the upper end of said main section 20 a supplemental section having its side bars slideable longitudinally in the guides of the main section, and plates secured to the side bars of the supplemental section and having wings operating in the slots of the main section, substantially as set forth.

STEPHEN S. GROVES.
